UNITED STATES PATENT OFFICE

EDWARD THORNDIKE LADD, OF LEWISTON, NEW YORK, ASSIGNOR TO ISCO CHEMICAL COMPANY, INC., OF NIAGARA FALLS, NEW YORK, A CORPORATION OF NEW YORK

APPARATUS FOR MAKING BLEACHING POWDER

Application filed October 26, 1929. Serial No. 402,614.

My device relates in general to an apparatus for continuously making bleaching powder commonly known as chloride of lime.

The principal object of my invention has been to provide a device by which bleaching powder may be continuously made and collected by chlorinating lime hydrate while freely falling in a finely divided state through a chlorinated atmosphere.

10 Another object has been to provide a device whereby a desirable commercial bleaching powder may be continuously produced in marketable quantities.

Another object has been to provide a continuous discharge for the finished bleaching powder.

Moreover, it has been an object to provide a seal at the discharge of the device formed by the bleaching powder, whereby the device 20 will be sealed at the bottom against the escape of the chlorine gas.

The objects and advantages have been accomplished by the device shown in the accompanying drawing, of which:

25 Fig. 1 is a vertical, sectional elevation of my complete device.

Fig. 2 is a plan view, taken on line 2—2 of Fig. 1.

The device shown in the accompanying 30 drawing comprises a chlorinating tower 5, preferably cylindrical in shape and of considerable height, at the upper end of which may be arranged a gyratory screen 6, which is driven by means of a motor 7. A feed

35 hopper 8 provided with a screw conveyor 9 may be arranged over the top of the tower for the purpose of feeding lime hydrate into the screen 6. By means of the screen the lime hydrate is caused to freely fall down through

40 the tower in a steady shower of well distributed particles.

Arranged at any suitable point in the tower is an inlet 10 for chlorine gas by which an atmosphere of chlorine is maintained within the tower, through which the particles of lime fall, thus exposing the lime hydrate to the gas which it absorbs.

Arranged at the bottom of the tower is a 45 hood 11, preferably cylindrical in shape and designed to be water cooled. This hood may

be in interspaced relation with the floor 12, which is also water cooled. Suitable connections (not shown) are, of course, provided for circulating cooling water through the hood 11 and the floor 12, whereby a certain amount of heat of combination may be dissipated. The hood and floor are considerably larger in diameter than the tower so that as the partially finished product is fed outwardly over the floor and through the discharge opening, it will be further exposed to the chlorinating atmosphere.

Arranged on top of the floor 12 is a plow 13 which has a plurality of paddles 14 and 15, arranged preferably in angular relation as shown in Fig. 2. The paddles on each side of the shaft 16 to which the plow is attached are staggered so that the partially finished product will be repeatedly tumbled during its travel across the floor. The shaft 16 passes up through the floor 12 and is rotated by any suitable means (not shown).

The plow 13 is continuously rotating during the operation of the apparatus, and the partially chlorinated bleaching powder which has fallen on top of the floor 12 accumulates thereon and is moved outwardly into and accumulates in the discharge space between the top of the floor 12 and the bottom edge of the hood 11 until it forms a complete seal against leakage of the chlorine gas. In its horizontal movement toward the discharge opening, the partially chlorinated product becomes completely chlorinated. After the seal has been formed, continued 50 depositing of the chlorinated product upon the floor will cause a continuous or intermittent discharge out through the space from the device while at the same time maintaining the seal. Obviously, the finished product is collected by any suitable and well known means.

It is well known to those skilled in the art that a good commercial bleaching powder is chlorinated between 35% and 38%, and wherever in this description or in the appended claims I refer to the finished chlorinated product, I mean a product of substantially this degree of chlorination.

Wherever in the appended claims the term

"tower" is used, it is to be understood that it refers to the tower 5 which is so constructed that the particles of lime hydrate may freely fall within it and not be obstructed in such descent until they reach the bottom of the tower, after passing vertically through the chlorinated atmosphere. Furthermore, wherever the term "solid material" is used in the claims, I mean lime hydrate in powder form.

Obviously, various modifications of the details herein shown and described may be made without departing from the spirit of my invention or the scope of the appended 15 claims; as, for example, a rectangular or other cross-sectional shape for the chlorinating compartment, other means for feeding lime hydrate, other means for discharging the chlorinated product either continuously 20 or intermittently, and the like; and I do not, therefore, wish to be limited to the exact embodiment herein shown and described, the form shown being merely a preferred embodiment thereof.

Having thus described my invention, what I claim is:

1. An apparatus for making bleaching powder, comprising a relatively high chlorinating tower, means for creating a chlorinated atmosphere within the tower, means located near the top of the tower for sprinkling distributed particles of lime hydrate into the tower, the walls of the tower being so formed that the particles of lime hydrate will fall 30 freely by gravity from its top to its bottom through the chlorinated atmosphere, a hood at the bottom of the tower, means arranged at the bottom of the tower for receiving the chlorinated product, and means for discharging such product from the apparatus.

2. An apparatus for making bleaching powder, comprising a relatively high chlorinating tower, means for creating a chlorinated atmosphere within the tower, means located near the top of the tower for sprinkling distributed particles of lime hydrate into the tower, the walls of the tower being so formed that the particles of lime hydrate will fall freely by gravity from its top to its bottom 40 through the chlorinated atmosphere, a hood at the bottom of the tower, a floor arranged under the hood and in interspaced relation therewith, and means for discharging the chlorinated product out through the space between the hood and the floor.

3. An apparatus for making bleaching powder, comprising a relatively high chlorinating tower, means for creating a chlorinated atmosphere within the tower, means located near the top of the tower for sprinkling distributed particles of lime hydrate into the tower, the walls of the tower being so formed that the particles of lime hydrate will fall 50 freely by gravity from its top to its bottom through the chlorinated atmosphere, a hood 60

at the bottom of the tower, a floor arranged under the hood and in interspaced relation therewith, and a plow for discharging the chlorinated product into and out through the space between the hood and the floor.

4. An apparatus for making bleaching powder, comprising a relatively high chlorinating tower having walls forming a chamber free of obstructions, means located near the bottom of the chamber for supplying chlorine gas to the chamber and directing it upwardly therethrough thus creating and maintaining a chlorinated atmosphere within the chamber, distributing means located near the top of the chamber for uniformly 70 sprinkling particles of lime hydrate into the chamber so that all of such particles will fall by gravity uninterruptedly through the chamber from its top to its bottom and thus be exposed to the chlorinated atmosphere, a hood at the bottom of the chamber, a floor arranged under the hood and in interspaced relation therewith, and a multi-vane plow for 75 continuously discharging the chlorinated product out through the space between the hood and the floor.

5. An apparatus for making bleaching powder, comprising a relatively high chlorinating tower having walls forming a chamber free of obstructions, means located near the bottom of the chamber for supplying chlorine gas to the chamber and directing it upwardly therethrough, thus creating and maintaining a chlorinated atmosphere within the chamber, distributing means located near 80 the top of the chamber for uniformly sprinkling particles of lime hydrate into the chamber so that all of such particles will fall by gravity uninterruptedly through the chamber from its top to its bottom and thus be exposed to the chlorinated atmosphere, a hood at the bottom of the chamber, a floor arranged under the hood and in interspaced relation therewith, and a multi-vane plow for 85 continuously discharging the chlorinated product out through the space between the hood and the floor.

6. An apparatus for making bleaching powder, comprising a relatively high chlorinating tower, means for creating a chlorinated atmosphere within the tower, a shaker element located near the top of the tower for distributing particles of solid material into the tower, the walls of the tower being so formed that such particles will fall freely by 90 gravity from its top to its bottom through the chlorinated atmosphere, and a plow for discharging such product from the apparatus.

7. An apparatus for making bleaching powder, comprising a relatively high chlorinating tower having walls forming a chamber free from obstructions, means for creating a chlorinated atmosphere within the chamber, a shaker element located near the 100

top of the chamber for continuously distributing particles of solid material into the chamber, so that such particles will fall uninterruptedly through the chamber from its 5 top to its bottom, and means for continuously discharging such product from the chamber.

8. An apparatus for making bleaching powder, comprising a relatively high chlorinating tower having walls forming a chamber 10 free from obstructions, means for creating a chlorinated atmosphere within the chamber, a shaker element located near the top of the chamber for distributing particles of solid material into the chamber, so that such particles 15 will fall uninterruptedly through the chamber, means located at the bottom of the chamber for receiving the chlorinated product and for forming a discharge opening around its periphery, and a plow for discharging such product through the discharge opening.

In testimony whereof, I have hereunto signed my name.

EDWARD THORNDIKE LADD.
